E. SCOFIELD,
DOUBLE SEAL FRICTION CAP.
APPLICATION FILED JUNE 10, 1921.

Patented Aug. 22, 1922.

UNITED STATES PATENT OFFICE.

EDGAR SCOFIELD, OF NEW YORK, N. Y., ASSIGNOR TO ANCHOR CAP AND CLOSURE CORPORATION, OF LONG ISLAND CITY, NEW YORK, A CORPORATION OF NEW YORK.

DOUBLE-SEAL FRICTION CAP.

1,426,917.

Specification of Letters Patent. Patented Aug. 22, 1922.

Application filed June 10, 1921. Serial No. 476,423.

To all whom it may concern:

Be it known that I, EDGAR SCOFIELD, a citizen of the United States, residing at New York, in the county of New York, State of New York, have invented certain new and useful Improvements in Double-Seal Friction Caps, of which the following is a specification.

This invention relates broadly to packaging and more specially to a friction seal cap and a package made with this cap.

The principal object of the present invention is a friction seal cap having a plurality of sealing zones wherein the effective sealing pressure is distributed throughout the sealing zones.

Another object of the present invention is a friction cap provided with a plurality of sealing zones having stiffened force transmitting means arranged between the sealing zones in such manner that the sealing forces of one zone are transmitted to the sealing area of another zone whereby the several zones cooperate with one another to produce an effective seal.

A further object of the present invention is, more specially, a friction cap provided with a yieldable skirt and having a plurality of sealing zones arranged therein with a force transmitting zone between the sealing zones and wherein the force transmitting zone is stiffened in the direction of the length of the skirt and is adapted to yield circumferentially of the skirt.

Another and more specific object of the present invention is a friction seal cap having a skirt depending from a cover portion with a circumferential sealing zone near the cover portion and with a ribbed section beneath the sealing zone and a second sealing zone below the ribbed section.

Another and specific object of the present invention is a closure cap of the friction type having a skirt provided with a plurality of sealing zones and wherein the yield of the sealing zones during the sealing operation is toward an area or zone which is between the sealing zones and wherein both the upper edge and the lower edge of the cap are formed in such manner as to resist stretching.

Another and specific object of the present invention is a friction sealing cap having a skirt depending from a cover portion and with a plurality of annular sealing zones

provided in the skirt and with outwardly extending knurling between the sealing zones.

Another and specific object of the present invention is a friction sealing cap having a skirt depending from a cover portion and with a plurality of annular sealing zones provided in the skirt and with constricting means between the sealing zones to normally exert a sealing pressure on a container when the cap is in place.

A still further and important object of the present invention is a package formed by a cap as specified in the foregoing paragraphs being applied to a vessel having substantially incompressible side walls such as a glass jar or the like.

Other and further objects will in part be obvious and will in part be pointed out hereinafter by reference to the accompanying drawings and wherein like parts are represented by like characters throughout the several figures thereof.

Realizing that the present invention may be embodied in constructions other than those specifically shown and described it is to be understood that the disclosure here-with is merely illustrative and is in no way intended to be taken in the limiting sense.

Figure 1 is a perspective view illustrating a package formed by a glass jar or the like and a cap comprising the present invention applied to the mouth of the said jar.

Figure 2 is a fragmentary sectionized portion of the side wall of the container and the skirt of the cap and illustrating the cap prior to being applied.

Figure 3 is a view similar to Figure 1 showing the cap as partially telescoped over the end of the container wall so that one sealing zone is effective, and illustrating the active forces in the skirt at this time.

Figure 4 is a view similar to Figure 3 and illustrates forces which are active when the second sealing zone is passing over the side wall of the container.

Figure 5 illustrates a cap in position and is a section through the outer portion of one of the corrugations.

Figure 6 is a view similar to Figure 5 illustrating a section through the valley or inner portion of one of the corrugations.

Figure 7 is a plan view showing a horizontal section taken through line 7-7 Figure 6.

In the commercial art of packaging it has become common practice to package certain solid or plastic substances in containers having friction cap covers, which caps are adapted for removal without destruction so that the cap may be re-used simply as a cover, while the contents of a container are being consumed. One of the oldest types of such friction covers comprises a cap with a plain cylindrical skirt. This type of cap encountered many difficulties due to the fact that commercial glass is seldom an exact size or shape. Since the metal caps were made by mechanical dies, the caps were substantially of uniform shape and size. The result was that ordinary slip caps that were accurate would not fit glass that varied and such caps were not adapted to seal glass of the ordinary commercial run with the variations which are commercially acceptable. The next step in the art was that of providing a slip cap with a skirt having an inwardly extending groove of such depth and shape as to slightly stretch and with the groove positioned in a cap in such manner as to permit the sealing zone to occur a sufficient distance downward on the side wall of the skirt below the cover to permit the skirt to flex and conform both in size and shape to glass and thereby accommodate glass which departed, within commercial standards, from the size and shape being sealed. In this type of cap the sealing forces, due to elasticity of the metal, were concentrated on a single zone and, if for any reason, this portion of the metal was stretched beyond the elastic limit there was a liability of the seal becoming ineffective.

The present invention overcomes the difficulties of the known art by providing a cap having a plurality of circumferential seals, or gripping zones, with the arrangement of the zones being such that the sealing forces in one zone are transmitted to, and reinforce, the active sealing forces in another zone. This action greatly increases the holding qualities of the cap as well as increases the safety factor of the security of the seal. While it is desirable it is, nevertheless not essential, that all the sealing zones shall be dust or air tight. One of the zones may comprise a circumferential continuous contact seal while the other is of the interrupted form, or under certain conditions both the zones may be of the interrupted form.

One embodiment of the present invention comprises a cap having a restricted portion, comprising a sealing zone near the cover, with an outwardly knurled portion adjacent the restricted part, and with a second restricted portion comprising a sealing zone adjacent the lower part of the knurling. The walls of the second restriction are continued outward and preferably are finished by doubling the metal upon itself to form a

wire bead common to the metal working art. The cap is applied by telescoping the same over the side wall of a glass jar or the like having a circumference slightly greater than the inside circumference of the sealing zones. 70 This sets up forces in the sealing zones which forces are transmitted in both directions from the sealing zones; to the wire edge on one side of the lower sealing zone and to the top or cover on the other side of 75 the upper sealing zone. Both the wire edge and the top act as abutments tending to resist the force produced by stretching at the sealing zone. Since these forces are resisted by the abutment the forces are therefore 80 transmitted to or thrown into the knurled part of the cap between the sealing zones. This knurled part is stiff in the longitudinal direction of the skirt of the cap but is capable of yielding circumferentially 85 in view of the fact that the caps are made of sheet tin or the like which is an elastic material. The knurling produces an elastic field which acts as a constricting spring that yields sufficiently to prevent the sealing 90 action to take place and uses the stored energy put in by the sealing action to pull or resist circumferential stretching. The sealing zones therefore are continually under a spring constricting action tending to 95 maintain the sealing zones under efficient sealing pressure at all times. In view of the fact that the knurled portion of the skirt is stiff in a direction of the length of the skirt it therefore follows that the sealing 100 forces from the lower zones are transmitted through these stiffened ribs to the upper zone and when the upper zone passes over a glass or the like, side wall the sealing forces active in the upper zone are transmitted back to increase the sealing action at 105 the lower zone.

Referring now to the drawings which illustrate one embodiment of the present invention the cap may comprise a cover portion 1 from which extends a downwardly depending skirt having a sealing zone 2 comprising an inwardly directed portion, with the convexed portion on the interior of the skirt and the concave portion on the 110 exterior of the skirt; and which sealing zone is in the upper portion of the skirt. An outwardly curved circumferential knurled portion 3 comprising ribs 4 and valleys 5 is provided adjacent the sealing zone 2. 115 This knurled portion is stiff in the direction of the length of the skirt, but is adapted to yield in the direction circumferentially of the skirt. A second restricted portion or sealing zone 6 is provided below the knurled 120 part 3 and the lower side wall of this sealing zone 6 is continued downwardly and outwardly in the form of a curve with the concave portion on the outer part of the skirt and the convexed portion on the inner part 125 130

of the skirt. The edge of the skirt is folded upon itself to provide a wire edge finish 8 as is common in the metal working art.

In the sealing operation the cap is placed 5 loosely on the mouth of a glass or similar container 9 as is illustrated in Figure 2. The cap is then telescoped over the mouth of the container by applying forces in the direction of the arrow A. The application of 10 the forces indicated by the arrow A causes a wedging action between the rounded upper end 10 of the side wall 9 of the container and the sealing zone 6, which action tends to stretch the sealing zone 6. The forces 15 tending to stretch this sealing zone 6 and to slightly flatten the curve are transmitted in both directions from the sealing zone 6. The forces transmitted to the edge of the cap are resisted by the reenforcement or 20 wire edge 8 which is twice the strength of a single thickness of the metal, therefore the reaction forces are transmitted into the knurled part 3 as is indicated by the arrows B in Figure 3. As the telescoping action 25 is continued the zone 2 begins to be active and the forces set up by the wedging of the wall 10 past the zone 2 likewise extends in both directions from the curve. The forces 30 extending upwardly are met and resisted by the strength of the top of the cover so that the effective active forces are therefore again transmitted into the knurled portion 3 and since the knurled portion is stiff in the direction of the length of the skirt these 35 forces are transmitted back against the sealing zone 6 so that the effective sealing forces in the lower zone is increased by the action of the sealing forces in the upper zone.

When it is desired to open the package 40 the skirt of the cap is either tapped gently with some tool having sufficient weight to slightly flatten the sealing zones 2 and 6 in the skirt against the side wall of the container as an anvil and permanently stretch 45 the skirt at the sealing zones so that the gripping or restricting action is destroyed sufficiently to permit the user to lift the cap and expose the contents of the vessel. This same stretching action may be obtained by 50 rolling the cap against a suitable surface or in any other mechanical way which tends to permanently stretch the skirt of the cap 55 sufficiently to break the sealing forces. From the foregoing it will appear that the present invention provides a simple friction seal which is made by telescoping a pre-formed cap over a substantially incompressible side wall and wherein a multiplicity of seals are provided between the cap and the 60 side wall. The sealing energy or forces are stored in the mechanically arranged structure of the cap and these stored forces continue to exert pressure on the sealing zones in such manner as tends to constrict the sealing 65 zones against the glass side wall and

thus maintain a plurality of seals until the skirt is permanently stretched to break the seal.

Having thus described my invention, what I claim is:

1. A closure cap comprising a cover portion, a skirt depending from said cover portion, a sealing zone in the upper portion of said skirt, another sealing zone in the lower portion of said skirt, and means between said sealing zones for transmitting the forces effective in one zone to the other zone. 70

2. A closure cap comprising a cover portion, a skirt depending from said cover portion, a continuous annular sealing zone in the upper portion of said skirt, another sealing zone in the lower portion of said skirt, and means between said sealing zones for transmitting the forces effective in one zone to the other zone. 80

3. A closure cap comprising a cover portion, a skirt depending from said cover portion, a sealing zone in the upper portion of said skirt, another sealing zone in the lower portion of said skirt, elastic means between said sealing zones for transmitting the forces effective in one zone to the other zone. 85

4. A closure cap comprising a cover portion, a skirt depending from said cover portion, a sealing zone in the upper portion of said skirt, another sealing zone in the lower portion of said skirt, and means between said sealing zones adapted to expand circumferentially and to transmit longitudinally the forces effective in one zone to the other zone. 95

5. A closure cap comprising a cover portion, a skirt depending from said cover portion, a sealing zone in the upper portion of said skirt, another sealing zone in the lower portion of said skirt, and means between said sealing zones for transmitting the forces effective in one zone to the other zone, and reenforcing means at the edge of the skirt. 100

6. A closure cap comprising a cover portion, a skirt depending from said cover portion, a continuous annular sealing zone in the upper portion of said skirt, another sealing zone in the lower portion of said skirt, and elastic means between said sealing zones for transmitting the forces effective in one zone to the other zone. 110

7. A closure cap comprising a cover portion, a skirt depending from said cover portion, a sealing zone in the upper portion of said skirt, another sealing zone in the lower portion of said skirt, and means between said sealing zones adapted to expand circumferentially and to transmit longitudinally the forces effective in one zone to the other zone, and reenforcing means at the edge of the skirt. 120

8. A closure cap comprising a cover portion, a skirt depending from said cover portion, a continuous annular sealing zone in the upper portion of said skirt, another seal- 130

- 1 ing zone in the lower portion of said skirt, elastic means between said sealing zones adapted to expand circumferentially and to transmit longitudinally the forces effective 5 in one zone to the other zone, and reenforcing means at the edge of the skirt.
9. A closure cap comprising in combination a cover portion, a skirt depending from said cover portion, a knurled zone in said skirt with the knurling being outward, and sealing zones on each side of said knurled portion.
10. A closure cap comprising in combination a cover portion, a skirt depending from 15 said cover portion, a knurled zone in said skirt with the knurling being outward and the direction of the ribs thereof being in the direction of the length of the skirt, and sealing zones on each side of said knurled portion.
11. A closure cap comprising in combination a cover portion, a skirt depending from 20 said cover portion, a knurled zone in said skirt with the knurling being outward, and sealing zones on each side of said knurled portion, with said sealing zones comprising annular ribs on the interior.
12. A closure cap comprising in combination a cover portion, a skirt depending from 25 said cover portion, a knurled zone in said skirt with the knurling being outward and the direction of the ribs thereof being in the direction of the length of the skirt, and sealing zones on each side of said knurled portion, with said sealing zones comprising annular ribs on the interior of the skirt.
13. A closure cap comprising a cover portion, a skirt depending from said cover portion, a pair of sealing zones in said skirt, 40 and constricting means between said sealing zones.
14. A closure cap comprising a cover portion, a skirt depending from said cover portion, a pair of sealing zones in said skirt, 45 and constricting means between said sealing zones and effective on both zones.
15. A closure cap comprising a cover portion, a skirt depending from said cover portion, a pair of sealing zones in said skirt, 50 and constricting means between said sealing zones in combination with a container having substantially incompressible sealing walls adjacent the mouth thereof.
16. A closure cap comprising a cover portion, a skirt depending from said cover portion, a pair of sealing zones in said skirt, 55 and constricting means between said sealing zones and effective on both zones, in combination with a container having substantially incompressible sealing walls adjacent the mouth thereof.
17. A closure cap comprising a cover portion, a sealing zone adjacent said cover portion in such manner that part of the sealing 60 forces are transmitted to the edge of
- said cover portion, a lower sealing zone in said skirt, strengthening means on the edge of said skirt and adapted to resist sealing forces from the lower zone, and means elastic in a circumferential direction and arranged between said sealing zones to absorb sealing forces from each zone. 70
18. A closure cap comprising a cover portion, a sealing zone adjacent said cover portion in such manner that part of the sealing forces are transmitted to the edge of 75 said cover portion, a lower sealing zone in said skirt, strengthening means on the edge of said skirt and adapted to resist sealing forces from the lower zone, and means elastic in a circumferential direction and arranged between said sealing zones to absorb sealing forces from each zone, said means being adapted to distribute the sealing forces from one zone to the other zone. 80
19. A closure cap comprising a cover portion, a sealing zone adjacent said cover portion in such manner that part of the sealing forces are transmitted to the edge of 85 said cover portion, a lower sealing zone in said skirt, strengthening means on the edge of said skirt and adapted to resist sealing forces from the lower zone, and means elastic in a circumferential direction and arranged between said sealing zones to absorb sealing forces from each zone, said means being adapted to distribute the sealing forces from one zone to the other zone. 90
20. A closure cap comprising a cover portion, a sealing zone adjacent said cover portion in such manner that part of the sealing forces are transmitted, to the edge of 95 said cover portion, a lower sealing zone in said skirt, strengthening means on the edge of said skirt and adapted to resist sealing forces from the lower zone, and means elastic in a circumferential direction and arranged between said sealing zones to absorb sealing forces from each zone, said means being adapted to distribute the sealing forces from one zone to the other zone, in combination with a container having substantially incompressible side walls at the 100 sealing zone. 105
21. A closure cap comprising a cover portion, a sealing zone adjacent said cover portion in such manner that part of the sealing forces are transmitted to the edge of 110 said cover portion, a lower sealing zone in said skirt, strengthening means on the edge of said skirt and adapted to resist sealing forces from the lower zone, and means elastic in a circumferential direction and arranged between said sealing zones to absorb sealing forces from each zone. 115
22. A closure cap comprising a cover portion, a sealing zone adjacent said cover portion in such manner that part of the sealing forces are transmitted to the edge of 120 said cover portion, a lower sealing zone in said skirt, strengthening means on the edge of said skirt and adapted to resist forces from the lower zone, and means elastic in a circumferential direction and stiff in a longitudinal direction and arranged between said sealing zones to absorb sealing forces from each zone, said means being adapted to distribute the sealing forces from one zone to the other zone, in combination with a container having substantially incompressible side walls at the sealing zone. 125
